UNITED STATES PATENT OFFICE.

HENRY J. BLAKESLEE, OF HARTFORD, CONNECTICUT.

REGULATING-TRANSFORMER.

No. 808,718.

Specification of Letters Patent.

Patented Jan. 2, 1906.

Application filed April 8, 1905. Serial No. 254,479.

To all whom it may concern:

Be it known that I, HENRY J. BLAKESLEE, a citizen of the United States, residing at Hartford, in the county of Hartford and 5 State of Connecticut, have invented a new and useful Regulating-Transformer, of which the following is a specification.

This invention relates to an alternating-current transformer which is designed to 10 regulate the current or electromotive force in circuits in which it is connected or which it supplies.

The object of the invention is to provide a 15 simple transformer of this class having a magnetic circuit of constant and low reluctance and without moving conductors or sliding contacts.

Alternating-current regulators which operate on the transformer principle, as previously built have either a movable primary coil and stationary secondary coil, or a movable secondary coil and stationary primary coil, or have both primary and secondary coils movable, a movable coil upon a magnetic core, either with or without stationary coils in series therewith, stationary, primary, and secondary coils with a movable core so arranged that the reluctance of the magnetic circuit is variable, a coil with a core of 25 variable magnetic reluctance, means for cutting in or out turns of a coil upon a magnetic core, means for cutting in or out turns of a primary coil or of a secondary coil, or various combinations of these several features.

30 An alternating-current-regulating transformer which embodies my invention has only stationary coils and a magnetic circuit of constant reluctance so arranged that the total magnetic flux is at all times inclosed by one coil, while from the minimum to the maximum magnetic flux is inclosed by the other coil automatically or at will, according to the required conditions.

Figure 1 of the accompanying drawings 45 shows a central longitudinal section of a regulating-transformer that embodies this invention. Fig. 2 shows an end view with one of the heads omitted. Fig. 3 shows a transverse section through the middle. Fig. 4 shows a central longitudinal section with the core omitted. Fig. 5 shows a central longitudinal section of a transformer of modified 50 construction. Fig. 6 shows an end view of this modified form without the head. Fig. 7 shows a transverse section through the middle of this latter form. Fig. 8 shows a cen-

tral longitudinal section of the modified form with the core omitted. Fig. 9 shows one head and a counterbalance that may be employed. Fig. 10 is a diagram illustrating 60 various ways the primary and secondary coils may be arranged.

The frame 1 of the transformer is built up of thin sheets of magnetic metal in a common manner. This laminated frame, which 65 is preferably cylindrical, is held together by any suitable means and at each end has a non-magnetic head 2. The primary coil 3, which is connected with the mains in the usual way, is located in an annular recess in 70 the middle of the frame, so as to encircle the core 4. The secondary coil 5, which may be connected with branch wires leading to lamps, motors, or heaters or to feed-wires, as 75 usual, is wound upon polar projections 6, that extend inwardly from each side of the middle of the cylindrical frame. There may be any desired number of polar projections, and the secondary coil may be wound upon or looped about these in many ways. In the 80 form of the invention that is first illustrated there are four polar projections at each end and the secondary coil encircles these polar projections, so that an edge of one loop overlaps an edge of the adjacent loop. In this 85 form the adjacent loops of the secondary coil are wound oppositely. In the second form illustrated the secondary coil passes back and forth through the spaces between the polar projections and alternately on the inside and 90 on the outside of the polar projections.

The core, which extends the length of the frame, is built up of iron sheets and is mounted on an arbor 7, that is supported by the heads. The two outer edges of the core are 95 curved and conform closely to the inner wall of the frame and the insides of the coils, while the two flat sides are some distance from the inner wall of the frame and the coils. The spaces between the sides of the core and 100 the coils may be left vacant, as shown in Fig. 3, or non-magnetic conductors 8 may be attached to the sides of the core, as shown in Fig. 7, for the purpose of decreasing the impedance of the loops opposite which they 105 may happen to be. The arbor may be provided with any common means for counterbalancing the magnetic torque of the core. In the form shown this counterbalance is a pulley 9, around which passes a cord 10, to 110 which a weight 11 is fastened.

In this transformer the stationary primary

coil always has the same relation to the frame and the core always has the same relation to the frame and the primary coil which encircles it. Consequently the magnetic reluctance will be constant.

In the form of the invention illustrated in Figs. 5 to 8 when the core stands in the position shown the maximum number of lines of force flux through the secondary coil, inducing therein a maximum electromotive force. If the core occupies a position ninety degrees from that shown in the drawings, the secondary would inclose a minimum number of lines of force and the electromotive force induced therein would be the minimum. The pull of the counterbalance always tends to bring the core to the position shown in the drawings, and the torque, due to the current in the secondary, tends to bring the core to a position ninety degrees from that shown. Therefore the core being provided with a properly designed and adjusted counterbalance it is evident that the secondary coil can be made to deliver approximately a constant current to a circuit of widely-varying impedance.

If the secondary coil is arranged as illustrated in Figs. 1 to 4 and the adjacent loops are wound and connected so that their electromotive forces oppose each other, it is evident that with the core in the position shown a maximum electromotive force will be induced in the loops nearest the edges of the core and a minimum electromotive force in the loops farthest from the edges of the core, and when the core is in a position at right angles to that shown a maximum electromotive force will be induced in the loops nearest the edges of the core and a minimum electromotive force in the loops farthest from the edges of the core. In this case, however, the direction of the current would be in one direction when the core is in the position shown and would be in the reverse direction when the core was at right angles to that position. When the core is in a position at forty-five degrees from that shown, the resulting electromotive force from the adjacent loops near the edges of the core, which are wound reversely and connected in series, would be zero. Therefore by connecting two such coils in series opposed and connecting them in series with the feeder it is evident that the electromotive force of the feeder may be either raised above or lowered below the electromotive force of the supply by changing the position of the core, the primary coil being connected to the supply in the usual manner.

A transformer embodying this invention may be used in connection with a constant-potential circuit for regulating a secondary circuit containing lamps or other electrical appliances connected in series, in which case the primary and secondary coils can be arranged as indicated at *a* in Fig. 10 or may

be used for raising or lowering the electromotive force of a feeder-circuit, in which case the primary coil can be connected in multiple and the secondary coil in series with the load, as indicated at *b* in Fig. 10, or may be used as a choke-coil for lamps or other appliances connected in series with a constant-current-feeder system, in which case the coils could be connected in series with each other and the load, as indicated at *c* in Fig. 10. There are other uses to which one of these transformers could be put—such as for starting, stopping, reversing, and regulating the speed of an alternating-current motor—which uses will be readily understood by an electrician, so will not be herein specified in detail. The number of polar projections or the number and arrangement of coils and the means for counterbalancing the torque of the core are immaterial and may be varied without departing from the invention, and, if desired, the core may be moved by hand instead of automatically for producing the desired effect.

The invention claimed is—

1. A regulating-transformer, having a cylindrical magnetic frame, a stationary primary coil, a stationary secondary coil, and a core with its axis extending perpendicular to the plane of the primary coil and movable within the frame and the primary and secondary coils, substantially as specified.

2. A regulating-transformer having a magnetic frame, polar projections on the interior of the frame, a stationary primary coil in the interior of the frame, a stationary secondary coil encircling polar projections from the interior of the frame, and a magnetic core movable within the frame and the coils, substantially as specified.

3. A regulating-transformer having a magnetic frame, polar projections on the interior of the frame, a stationary primary coil encircling the interior of the frame, a stationary secondary coil encircling polar projections from the interior of the frame, a magnetic core movable within the frame and the coils, and a counterbalance connected with the core, substantially as specified.

4. A regulating-transformer having a magnetic frame, a stationary primary coil, a stationary secondary coil, and a core always having the same magnetic relation to the primary coil but adapted to be moved to vary its magnetic relation with the secondary coil, substantially as specified.

5. A regulating-transformer having a stationary magnetic frame and a movable core, a fixed primary coil arranged to always encircle the total flux through the core, and a fixed secondary coil so arranged that the flux through it varies from maximum to minimum according to the position of the core, substantially as specified.

6. A regulating-transformer having a cy-

- lindrical magnetic frame, polar projections on the interior of the frame, an annular primary coil fixed in the interior of the frame, a fixed secondary coil embracing polar projections from the interior of the frame, a core extending through the frame within the primary and secondary coils, and means for counterbalancing the magnetic torque of the core, substantially as specified.
10. 7. A regulating-transformer having a cylindrical magnetic frame, polar projections on the interior of the frame, a primary coil fixed in a recess in the middle of the frame, a secondary coil wound in reverse directions about polar projections from the interior of the frame, and a magnetic core extending through the frame and the primary and stationary coils, substantially as specified.
8. A regulating-transformer having a stationary magnetic frame, a fixed primary coil encircling the interior of the frame, a fixed secondary coil in the interior of the frame, and a magnetic core movable within the frame and the primary coil, the axis of the core extending perpendicular to the plane of the primary coil, and the said coils being arranged so that the primary always encircles the total flux through the core while the secondary varies from maximum to minimum
- according to the position of the core, substantially as specified.
9. A regulating-transformer having a stationary magnetic frame, a fixed primary coil encircling the interior of the frame, a fixed secondary coil in the interior of the frame, a magnetic core within the frame and the primary coil, the axis of the core extending perpendicular to the plane of the primary coil, and non-magnetic conductors attached to the core in such manner as to lie opposite inactive sections of the magnetic frame, substantially as specified.
10. A regulating-transformer having a stationary magnetic frame, a fixed primary coil encircling the interior of the frame, a fixed secondary coil in the interior of the frame, a magnetic core within the frame and the primary coil, the axis of the core extending perpendicular to the plane of the primary coil, and a counterbalance connected with and tending to rotate the core on its axis in a direction opposite to the magnetic torque, substantially as specified.
